CLAIM

The ornamental design for a wheelbarrow frame, as shown and described.

DESCRIPTION

FIG. 1 is a front perspective of a wheelbarrow frame;

FIG. 2 is a front view of a wheelbarrow frame;

FIG. 3 is a rear view of a wheelbarrow frame;

FIG. 4 is a right-side view of a wheelbarrow frame;

FIG. 5 is a left-side view of a wheelbarrow frame;

FIG. 6 is a top view of a wheelbarrow frame; and,

FIG. 7 is a bottom view of a wheelbarrow frame.

The broken line illustrations are shown in broken lines for illustrative purposes only and form no part of the claimed design.

1 Claim, 7 Drawing Sheets
